TYPEWRITING MACHINE

William F. Helmond, West Hartford, Conn., assignor to Underwood Elliott Fisher Company, New York, N. Y., a corporation of Delaware

Application May 14, 1937, Serial No. 142,528

2 Claims. (Cl. 197—35)

This invention relates to the muting of vibration in the type-bars of typewriters.

Vibration of the type-bar impedes its passage into the type-bar center guide, causes the type face to make an indistinct impression on the work-sheet, reduces the number of legible carbon copies, and increases the noise of typing and the work necessary for the operation of the type-bar.

10 It is an object of this invention to reduce or eliminate the vibrations of the type-bar and increase the legibility of the work-sheet, increase the number of legible carbon copies, minimize or eliminate the noise and decrease the energy expended by the typist.

One form of this invention is a type-bar made in longitudinal halves, of the same material and thickness, as each part may be half of the thickness of a standard type-bar. The halves are to be spot-welded together at one or more scattered points approximately along the longitudinal axis. The halves of the type-bar, being of the same thickness and material, will have the same sonorousness. When spot-welded together, so that the adjacent inner surfaces of the halves may be in contact, the vibrations of the type-bar will be reduced or eliminated. Each half may have a rounded longitudinal strengthening rib. When both halves have the ribs, they may 30 curve outwardly from the contacting surfaces, or the ribs may be so constructed that one rib will be of a size to fit or nest in the rib of the other half. The two halves may have a hole cut in that portion of the type-bar which is in 35 the segment. This hole is to be of such size and so placed that it will aid in muting the vibrations of the type-bar without impairing its strength.

Another form of this invention is a type-bar, 40 having a shortened, centrally positioned, vibration-muting metal strip, spot-welded, in one or more places, along one of its side surfaces. The metal strip may be shaped or bent so that when, at or near its end, it is spot-welded to the type-bar there will be uniform pressure between the contacting surfaces.

Another form of this invention is a type-bar, 45 having a slot cut in that portion farthest from the type-head. The slot is so located that the strength of the type-bar will not be impaired, and will form a portion or projection that will dampen the vibrations of the type-bar.

There is also shown a type-bar having a vibration-reducing, round hole located in the 50 hub portion of the type-bar. The hole is of such a size and location, that it will not impair the strength of the type-bar, but will remove that portion which usually has convex surfaces, or humps, which have been unavoidable when 55 grinding the type-bar by hand. Hence there is 60

secured an accurate fit of the type-bar in the slot of the segment.

A disk of a slightly smaller diameter, and from two to four thousandths less in thickness than the type-bar, may be inserted in the hole and held there by the enlarged, lower, portion of the segment. This vibration-dampening disk is rotatable both around its own axis and also around the fulcrum of the type-bar. The inertia generated by swinging the type-bar will 10 cause the disk to rotate on its own axis and it will carry and throw oil into the guide-slot, in the segment, in which the type-bar fits and a protective lubricating and vibration-dampening film of oil will be maintained on the contacting surfaces of disk, type-bar and segment. 15

Other features and advantages will herein-after appear.

In the accompanying drawings,

Figure 1 is a side elevation of a typewriter 20 showing the platen, segment and a center action.

Figure 2 is a side elevation of a type-bar made in two pieces.

Figure 3 is a section of Figure 2, taken along the approximate longitudinal line of weld points. 25

Figure 4 is a section of Figure 2 on the line 4—4.

Figure 5 is the same as Figure 4 except the ribs are nested.

Figure 6 is a side elevation of a type-bar, segment, and platen. 30

Figure 7 is an elevation of the same action shown in Figure 6. The type is near the point of contact with the work-sheet.

Figure 8 shows the type-bar of Figure 6 in 35 printing position.

Figure 9 is a partial section along a plane at right angles to plane of Figure 6.

Figure 10 is a section along the line 10—10 of Figure 6. 40

Figure 11 is an elevation of a type-bar having a metal strip spot-welded to it.

Figure 12 is an exploded plan view of Figure 11.

Figure 13 is a plan view of Figure 11. 45

Figure 14 is a section along the line 14—14 of Figure 11.

In Figure 1, the key-lever 20 of a type-action in an Underwood typewriter has been depressed, though usually held in a normal inoperative 50 position by the spring 22, by pressure on the key-button 21. The key-lever 20, which is pivoted on the rod 23, carries a headed pin 24, engaging a slot 25 cut in an arm 26 of the bell-crank 27, pivoted on the rod 28. The upper end of the 55 arm 29 of bell-crank 27, has a hole 30 in which is fastened one end of the wire 31. The other end of the wire 31 engages a hole 41 located in the type-bar 32, pivoted on the rod 33 mounted in the segment 34. Type-bar 32 has the type- 60

head 35 having types 36 for imprinting on the work-sheet 37 on the platen 38 which is carried by rod 39 that is mounted in the typewriter carriage (not shown). The segment 34 has the 5 stop-ring 40 and a type-bar guide 42 for engaging the projecting portion 43 of the type-bar 32. The universal bar 44 is held against a curved portion 45 of the type-bar 32 by the spring 46. The lower portion of the segment 34 has slots 47 10 into which a part 48 of the type-bar 32 fits. Having a slot 50 cut in the segment-engaging portion 48 of type-bar 32, in such a manner as to leave a projection 51, reduces the vibration of type-bar 32.

15 Figures 2-3-4 show a type-bar 32 constructed of halves 53 and 54. Halves 53 and 54 are spot-welded together at one or more loci 55. Loci 55 are located approximately along the axis of the type-bar 32, leaving the edges of 53 and 54 free. 20 The halves 53 and 54 may be of the same thickness and material and may be half the thickness of a standard type-bar. Therefore each half 53 and 54 has the same sonorousness and when spot-welded together along an axial line they will 25 mute any vibrations. One or both halves 53 and 54 may have ribs 56 and 57 for additional strength of the type-bar 32, and if both halves 53 and 54 have ribs 56 and 57 they may be constructed to curve away from each other, as shown 30 in Figure 4, or they may be constructed to nest as shown in Figure 5. Halves 53 and 54 may have a hole 58, located near the pivot rod 33 and cut so as not to impair the strength of the type-bar 32, and will aid in muting the vibrations 35 of type-bar 32. The type-bar 32, made of halves 53 and 54, pivots on the rod 33 mounted in segment 34, and has the hole 41 for wire 31, and is located and operated as shown in Figure 1.

40 In Figures 6-9 inclusive, the segment 34 has an enlarged slotted portion 59, which has the slots 47, into which the type-bars 32 fit. The type-bar 32, shown in these figures, has a hole 60 near the pivot rod 33 for muting the vibration. In hole 60 there may be inserted a disk 61 45 slightly smaller in diameter than hole 60, and from two to four thousandths thinner than type-bar 32. Disk 61 is held in position by the slotted enlarged portion 59 of segment 34. Oil may be placed in the segment slots 47 and will, from the 50 force of gravity, form a drop 62 at the bottom of disk 61, as shown in Figure 6. When type-bar 32 is swung on its pivot rod 33, disk 61 and oil drop 62 move in an arm around the pivot rod 33, and hold the same position in relation to 55 type-bar 32, as shown in Figure 7, as they had in Figure 6. When the type 36 strikes the work-sheet 37, backed by platen 38, the inertia causes disk 61 to turn on its axis and carry and throw the drop of oil 62 into the upper portion of slot 60 47, from where it distributes itself over sides of slots 47, the disk 61 and type-bar 32. This film of oil acts as lubricant and to mute the vibrations of the type-bar 32. Disk 61 is an aid for 65 muting vibration of type-bar 32.

65 In Figure 10, is shown how the hole 60 removes the portion 65 of type-bar 32 which has curved faces due to grinding by hand. The removal of this portion 65 gives a more accurate fit in slots 47 and reduces friction, thereby aiding in muting the type-bar 32.

70 In Figure 11, the type-bar 32 is pivoted on rod 33 in segment 34 similar to Figure 1. This type-bar 32 has a shorter metal strip 64 spot-welded

in one or more loci 55, along one side. The metal strip 64 may have a part of one end 66 straight or parallel with the type-bar 32, and the rest of the metal strip 64 curved toward the plane of type-bar 32, as shown in Figure 12. When welded 5 together as in Figure 13, the metal strip 64 will contact the type-bar 32 with uniform pressure throughout its length. The metal strip 64 mutes the vibrations of type-bar 32. Type-bar 32 may have a strengthening rib 57 which curves away 10 from the side where the metal strip 64 is, as shown in Figure 14.

The type-bar 32 may vibrate from one or all of the following causes: impact on the key-button 21, friction of the type-bar 32 in segment 15 slot 47, impact of type-bar 32 against stop-ring 40, impact and friction of the type-bar-guiding projection 43, and type-bar guide 42, impact of type-faces 36 on work-sheet 37, inertia of the type-action, and imperfect alignment of the 20 type-bar 32, or any of the parts of the type-action. This vibration impedes the progress of projection 43 in type-guide 42, causes imperfect contact between type 36 and work-sheet 37 which gives a blurred indistinct typed letter, causes the 25 force of impact of type 36 to be reduced, thereby reducing the number of legible carbon copies, causes an increase in the noise of operation of a typewriter, and causes an increase in work necessary for operating the type-action. 30

The vibration of type-bar 32 may be muted by constructing the type-bar as shown in Figure 1, as shown in Figure 2, as shown in Figure 6, with or without the disk 61, or as shown in Figure 11. 35

Variations may be resorted to within the scope of the invention, and portions of the improvements may be used without others.

Having thus described my invention, I claim:

1. In a typewriter, an elongate type-carrying 40 bar integral in its extent from end to end, a type head being secured to one end of said bar, said bar having a type-guide-entering neck-portion immediately below said type head, and a snubber strip attached to said bar solely for 45 the purpose of muting its vibrations, said strip being materially shorter than said bar and placed thereon, between the neck-portion and the opposite end portion of said bar, so that the ends of said strip do not overlap either of said portions 50 and hence do clear said portions, said opposite end portion of the bar being disposable in a type-bar-fulcruming segment.

2. In a typewriter, an elongate type-carrying bar integral in its extent from end to end, a type 55 head being secured to one end of said bar, said bar having a type-guide-entering neck-portion immediately below said type head, and a snubber strip attached to said bar solely for the purpose of muting its vibrations, said strip being ma- 60 terially shorter than said bar and placed thereon, between the neck-portion and the opposite end portion of said bar, so that the ends of said strip do not overlap either of said portions and hence do clear said portions, said opposite end portion 65 of the bar being disposable in a type-bar-fulcruming segment, said strip being of resilient material and being attached at only one of its ends to said bar, the remainder of the strip being unattached and resiliently sprung against 70 the side of the type-carrying bar substantially as set forth.

WILLIAM F. HELMOND.
